UNITED STATES PATENT OFFICE.

WILLIAM C. HILDEBRAND, OF GLENROCK, PENNSYLVANIA, ASSIGNOR OF
ONE-HALF TO JOSEPH DISE, OF GLENROCK, PENNSYLVANIA.

WINDOW-SCREEN.

No. 800,106.

Specification of Letters Patent.

Patented Sept. 19, 1905.

Application filed December 27, 1904. Serial No. 238,386.

To all whom it may concern:

Be it known that I, WILLIAM C. HILDEBRAND, a citizen of the United States, and a resident of Glenrock, in the county of York 5 and State of Pennsylvania, have made certain new and useful Improvements in Window-Screens, of which the following is a specification.

My invention is an improvement in window-

10 screens, and especially in adjustable window-screens which can be extended and contracted to fit windows of different sizes as well as to facilitate their insertion and removal from windows.

15 The invention has for an object to provide certain improvements in the devices for connecting the sliding sections of the screen; and the invention consists in certain novel constructions and combinations of parts, as will 20 be hereinafter described and claimed.

In the drawings, Figure 1 is a side view of 25 a screen embodying my invention. Fig. 2 is a cross-section on about line 2 2 of Fig. 1. Fig. 3 is a detail perspective view of the end 30 of one of the screen-sections, showing the clip applied and the rolling head and shaft in connection therewith; and Fig. 4 is a detail perspective view showing the clip and rolling-head. Fig. 5 is a detail perspective view of 35 the end of one of the side bars, and Fig. 6 is a detail longitudinal section on about line 6 6 of Fig. 1.

As shown, the screen comprises the two sections A A, which are alike and have their 35 side bars B provided in their inner faces with the undercut grooves C, in which fit the rolling heads D, carried on the opposite sections. These heads D are on the outer ends of shafts E, which latter extend through the outer opening 40 of the undercut groove of the side bar B, carrying the head, and are journaled in the clip F, applied to the end of the side bar B, as best shown in Fig. 3 of the drawings, and as I will now describe.

45 The clips are alike and are formed with the side plates F' and end plate F² and are applied to the ends of the side bars B, with the outer side plate F' lapping against the outer face of the side bar, the opposite side plate F' fitting within the undercut portion of the 50 groove C, and the end plate F² abutting the end of the side bar, as best shown in Figs. 1 and 3 of the drawings. The head D is on one

end of the shaft E, which latter is journaled in the side plates of the clip and is upset at 55 its outer end. In practice the shaft revolves freely in the side plates of the clip and the head may roll within the groove, and thus permit the sections to slide freely along each other, the head operating to maintain the sections in connection with each other as desired.

The construction is simple, easily applied, forms a secure connection between the two sections, and permits the same to move easily 60 along each other in the practical use of the invention.

Having thus described my invention, what I claim as new, and desire to secure by Letters Patent, is—

1. The combination substantially as herein described of the screen-sections slideable one upon the other and having their side bars provided in their inner or adjacent faces with undercut grooves, the clips applied to the ends 75 of the side bars of the screen-sections and having their outer plates abutting the outer faces of the side bars, their end plates fitting against the ends of said side bars and their inner side plates fitting within the undercut 80 portions of the grooves of their respective side bars, and the shafts journaled in the side plates of the clips and upset at their outer ends and provided at their inner ends with the heads adapted to roll within the undercut 85 groove of the screen-section opposite that by which the said head and shaft are carried, substantially as set forth.

2. The combination in a window-screen with the sliding screen-sections having undercut 90 grooves, of clips applied to the ends of the side bars of said sections and shafts journaled in said clips and having heads operating in the undercut grooves of the section opposite that carrying the particular shaft, substantially as set forth.

3. A screen-section having its side bars provided with undercut grooves, clips applied to said side bars and shafts journaled in said clips and provided with heads which operate 100 in the undercut groove of a mating section, substantially as set forth.

4. The combination with sliding screen-sections having undercut grooves, of transverse shafts journaled in connection with the said 105 sections and having heads operating in the un-

dercut grooves of the opposing sections, substantially as set forth.

5. An attachment for window-screens comprising a clip having opposite side plates and an end plate and a shaft journaled in said side plates and having a head at one end adapted to operate in an undercut groove of a screen-section, substantially as set forth.

6. In a window-screen, the combination of the sliding screen-sections having undercut grooves, the clips having opposite side plates and an end plate and applied to the ends of the side bars of said sections and provided with transverse shafts journaled in the side plates of the clips and having heads at one end adapted to operate in the undercut grooves of

the sections opposite that carrying the particular shaft, substantially as set forth.

7. The combination of the screen-sections 20
slidable face to face and provided in the inner faces of their side bars with coincident undercut grooves, transverse shafts connected with the said sections and extending between the same and provided at their ends opposite the ends connected with their supporting-sections 25
with heads turning in the undercut grooves of the opposing sections, substantially as set forth.

WILLIAM C. HILDEBRAND.
